UNITED STATES PATENT OFFICE.

CHARLES SCOTT ALTHOUSE, OF READING, PENNSYLVANIA.

PROCESS OF SINGEING STOCKINGS.

1,269,148.

Specification of Letters Patent. Patented June 11, 1918.

Application filed September 22, 1917. Serial No. 192,676.

To all whom it may concern:

Be it known that I, CHARLES SCOTT ALTHOUSE, a citizen of the United States, residing at Reading, in the county of Berks 5 and State of Pennsylvania, have invented certain new and useful Improvements in Processes of Singeing Stockings, of which the following is a specification.

This invention relates to improvements 10 in the art or process of singeing stockings and the object in the present invention is to singe the stockings in large numbers, whereby the work is accomplished very much more rapidly than has been done heretofore.

In the manufacture of stockings, one step 15 consists in singeing them, that is, removing the nap from the outer surface of the stockings, and this has usually been accomplished by placing each stocking over a form and then subjecting them, while stretched on the form, to a singeing flame.

Various devices have been used in this 20 step, but in all of them it has been necessary to handle each article separately, both in placing it on the form and in removing it therefrom, as well as subjecting them either one at a time, or in relatively small numbers, to the singeing flame.

25 In my present invention I contemplate singeing the stockings in relatively large numbers and in loose form, that is, *en masse*, thus dispensing with the forms and the necessary labor of placing them on and removing them from these forms.

In the drawing accompanying this application, and forming a part thereof, I have shown a simple device whereby my process of singeing may be carried out.

30 The numeral 1 designates a vertical stack, provided at its upper extremity with a hopper 2, into which the stockings may be thrown in large numbers, or into which they may be thus fed continuously if desired.

35 Figure 1 is a vertical sectional view of a simple form of device for carrying out my invention. Fig. 2 is a front elevational view of a modified form of device for accomplishing the same purpose.

40 The stack may be made in any desired form that will readily admit the heat to its interior, as for instance, it may be composed of an open mesh screen as designated by the numerals 3, 4 and 5.

Surrounding the stack 1 is a casing 6, between which and the stack there is formed an air chamber 7.

45 The numeral 10 designates a fuel supply pipe, as for instance gas, and this supply pipe is formed with a series of jets 11.

50 These jets may project through the wall of the casing 6 so that the heat therefrom will enter the interior of the stack through the open mesh comprising its wall.

55 It may be more practicable in some instances however, to utilize a solid metal stack, and when this is used the jets of flame will impinge upon its outer surface and thus heat the interior thereof sufficiently to produce the desired singeing effect on 60 the stockings passing through the stack.

65 The numeral 15 designates any suitable receptacle for receiving the stockings as they pass out of the lower extremity of the stack.

70 When it is desired to singe the stockings, 75 they are fed into the hopper 2, in loose form, and the jets are lighted. As they pass downwardly through the stack they will be subjected to a continuous singeing heat.

75 The length of the stack and the degree of 80 heat may be readily regulated so that by the time the stockings shall have passed through the stack, their surfaces will be properly singed.

85 It is of course evident that modifications 90 of the device illustrated may readily be made, as for instance the stockings may be placed in a revolving drum, as shown in figure 2 of the drawing in which there are provided one or more large gas flames, and 95 the stockings will be tumbled therein until their entire surfaces have been subjected to the flame and they are properly singed.

95 I do not desire to limit myself to any specific form of apparatus, inasmuch as the 95 present invention contemplates singeing stockings either by direct or indirect application of the singeing element.

What I claim is:—

1. The process of singeing stockings 100 which consists of directing and causing them to pass in loose form and in large numbers through a singeing heat.

2. The process of singeing stockings 105 which consists of directing and causing them to pass, in loose form through a singeing flame.

3. The process of singeing stockings

which consists of directing and causing them to pass in loose form through a heated chamber.

4. The process of singeing stockings which consists in tumbling relatively large numbers of stockings in loose form through a flame.

5. That step in the art of singeing stockings which consists in subjecting them, in loose form, to a singeing heat.

6. The art of singeing stockings without preparing them individually, which consists in subjecting them, in relatively large numbers, to a series of flames.

7. The process of singeing relatively small textile articles which consists in tumbling them in loose form through a heated chamber.

In testimony whereof I affix my signature.

CHARLES SCOTT ALTHOUSE.
